Primary Examiner — Andrew T Nemeth(57) **CLAIM**

The ornamental design for a pet vest, as shown and described.

DESCRIPTION

FIG. 1 is a perspective view of a pet vest showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the pet vest where the pet vest is in an open state.

The broken lines in the drawings depict portions of the pet vest that form no part of the claimed design.

1 Claim, 9 Drawing Sheets(56)
